Edwin R. Storm

UNITED STATES PATENT OFFICE.

EDWIN R. STORM, OF NEW YORK, N. Y.

DIVISIBLE SHELF.

SPECIFICATION forming part of Letters Patent No. 660,264, dated October 23, 1900.

Application filed June 1, 1900. Serial No. 18,787. (No model.)

To all whom it may concern:

Be it known that I, EDWIN R. STORM, a citizen of the United States, residing at New York, in the county of New York and State of New York, have invented a new and useful Divisible Shelf, of which the following is a specification.

My invention relates to shelving or stands for books, cards, photographs, or other articles which it is desired to place on edge and hold in an upright position; and the objects of my invention are, first, to provide a shelf with partitions for dividing the shelf or stand into suitable spaces for the reception of books or articles, and, second, to provide a partition that may readily be adjusted to place or readjusted whenever it may be desired to change the spacing. I attain these objects by means of the devices illustrated in the accompanying drawings, in which—

Figure 1 is an isometrical projection of the shelf or stand with a number of the partitions indicated. Fig. 2 is a cross-section of the shelf or stand, showing the holes in the base and back-piece. Fig. 3 is a view of one of the partitions. Fig. 4 is an end view of the shelf or stand, showing the partition in place. Fig. 5 is a cross-section of the shelf or stand, showing a form of sheet-metal construction. Fig. 6 is an end view of the shelf or stand, showing two shelves joined back to back, forming a double shelf or stand.

Similar letters and figures refer to similar parts throughout the several illustrations.

The shelf or stand shown in Fig. 1 consists of a base 1 and a back-piece 2 and is formed of any suitable material and joined at 3 in any convenient manner, so that the back-piece 2 will be perpendicular to the base 1, as indicated. The base 1 is provided with the holes 4, which are placed near each other in a line parallel to the front edge of the base 1. The upper edge of the back-piece 2 is provided with the series of holes 5, registering with the holes 4 and in a line parallel thereto. The movable partitions 6, formed as indicated at Fig. 3, have their ends *a* fitted to enter the holes 4 and their ends *b* fitted to enter the holes 5. The portion *c* is formed to extend from the end *a* near the surface of the base 1 toward the back-piece 2. The portion *d* is formed to extend away from the base 1

and is inclined toward the back-piece 2. The portion *c* extends from the portion *d* to the end *b* and is joined therewith. The base 1, 55 with the back-piece 2, having been placed as a stand on a table or desk or as a shelf on any suitable support, and any partition 6 having its end *a* inserted in any desired hole 4 and its end *b* in the hole 5 registering therewith, 60 will be held firmly in place, any book or article desired to be held in an upright position being placed on the base 1, with one edge against the back-piece 2 and one side against the partition 6, and another partition 6 being placed 65 in position with its end *a* inserted in the hole 4 nearest the book or article, and end *b* in the hole 5 registering therewith will be held along its lower edge and along a perpendicular edge sufficiently to maintain it in an upright position. Upon removing the book or article the space which it occupied on the stand or shelf remains an allotted portion ready to receive the book or article. Upon returning the book or article to the shelf or stand the portions *c* of the partition 6 act as guides to direct the book or article in its movement, while the portions *d* by reason of their inclination act as guides to place the advancing perpendicular edge between the portions *e* of 80 the partitions 6.

It is evident that if it be desired to have a wider or narrower book or article occupy the space between the two partitions 6 set up one of them may be moved to any other hole 85 4 and its registering hole 5 and also that the whole shelf or stand may be divided as desired by setting up a suitable number of partitions 6.

As indicated in Fig. 5, the base 1 and back-piece 2 may be formed of sheet metal.

In Fig. 6 is shown a variation in which the base 1 is provided with a row of holes 4 along two edges and a back-piece 2 placed along the center line midway between the two rows 95 of holes A, the upper edge of the back-piece 2 being provided with two rows of holes 5, thus forming a double shelf or stand.

Having described my invention, I claim and desire to secure by Letters Patent—

1. The combination in a divisible shelf of a base having a series of holes, a back-piece joined to the base, having a series of holes registering with the holes in the base, and

movable partitions having ends adapted to enter and be held by the holes in the base and back-piece.

2. The combination in a divisible shelf of a base having a series of holes a back-piece joined to the base, having a series of holes registering with the holes in the base, and movable partitions having an edge extending away from the base and inclined toward the back-piece and ends adapted to enter the holes.

3. In a divisible shelf a movable partition having a portion extending from the front toward the back of the shelf, a portion extending away from the base-shelf, and inclined toward the back, a portion extending to the back and ends adapted to hold the partition in place.

4. The combination in a divisible shelf of a base having a series of holes parallel to its front edge, a back-piece having a series of holes in its upper edge, said series being parallel to and registering with the series of

holes in the base, and movable partitions each having an end adapted to enter a hole 25 in the base, a portion parallel to the base extending from said end toward the back, a portion inclined from the front toward the back, a portion extending to the back-piece and an end adapted to enter a hole in the 30 back-piece.

5. The combination in a divisible shelf of a base 1 having a series of holes 4 a back-piece 2 having a series of holes 5 registering with the holes 4 a movable partition 6 having an 35 end a adapted to enter and be held by the hole 4 a portion c extending from the front toward the back of the base 1, a portion d extending away from the base 1 and inclined toward the back-piece 2 a portion e extending to the back-piece 2 and an end b adapted to enter and be held by the hole 5.

EDWIN R. STORM.
